ELMER EDGAR CORNWELL AND JOSEPH HARRY McCREADY, OF OKMULGEE,
OKLAHOMA.

BURNER.

1,405,101.

Specification of Letters Patent. Patented Jan. 31, 1922.

Application filed February 19, 1921. Serial No. 446,217.

To all whom it may concern:

Be it known that we, ELMER EDGAR CORNWELL and JOSEPH HARRY McCREADY, citizens of the United States, and residents of Okmulgee, in the county of Okmulgee and State of Oklahoma, have invented certain new and useful Improvements in Burners, of which the following is a specification.

The present invention relates in general 10 to burners and more particularly to a gas burner especially adapted for return tubular boilers and stills.

The object of the invention is to provide a burner of this character which is of simple 15 and durable construction, reliable in operation and easy and inexpensive to manufacture and apply and which provides for a thorough, uniform and efficient mixture whereby the fuel is completely consumed 20 and a maximum amount of heat is evolved therefrom.

Other objects and advantages reside in certain novel features of the construction, arrangement and combination of parts which 25 will be hereinafter more fully described and particularly pointed out in the appended claims, reference being had to the accompanying drawings forming part of this specification, and in which—

30 Figure 1 is a side elevational view of the burner embodying the invention,

Figure 2 is a longitudinal sectional view therethrough,

Figure 3 is an end elevational view 35 thereof,

Figure 4 is a transverse sectional view.

Referring to the drawings wherein for the sake of illustration is shown the preferred embodiment of the invention, the numeral 40 10 designates an enclosed annular fuel chamber which is preferably of integral construction and comprises inner and outer circular walls 11 and 12 respectively, spaced from each other and integral with lateral walls or 45 faces 13 and 14 which complete the structure.

These walls define an annular fuel space 15 and the fuel chamber is adapted for connection with the fuel supply by means of an internally threaded nipple 16 or the like. The 50 inner circular wall 11 of the fuel chamber defines an axial inlet 17 for the air and a swinging plate 18 arranged at one end of the inlet constitutes a damper therefor, it being pivoted to the fuel chamber and se-

cured thereto in adjusted position by means 55 of a bolt and nut 19. The lateral face or wall 18 of the fuel chamber is provided with a circular series of discharge openings designated at 20 from which the fuel is projected.

The mixing chamber is arranged in co-operative relation to the fuel chamber and consists of an open ended shell 21 which has its inlet end adjacent the fuel chamber of circular form and which is flattened for a major portion of its length and to the opposite or discharge end of the shell so as to assume a substantially elliptical form as may be seen by a comparison of Figures 1 and 3. The fuel chamber and the circular open end of the mixing chamber define a substantially annular inlet for the air designated at 22. It is thus seen that when the damper 18 is open and the fuel is being projected from the discharge orifices 20 that it entrains an inner and an outer layer or strata of air 60 65 and is thus surrounded on all sides by the air and during its travel through the mixing chamber it is thoroughly commingled therewith to produce a uniform, complete and highly efficient mixture.

Means is provided for maintaining the fuel chamber and the mixing chamber in proper relation and for adjusting these chambers with respect to each other so that the proper relation may be obtained under 70 various conditions. This means includes a plurality, preferably a pair, of slotted arms indicated at 23 and arranged at diametrically opposite points with respect to said chambers. The arms are integral or otherwise secured to the mixing chamber and are offset to extend along the exterior wall of the fuel chamber. They are bifurcated or otherwise formed to define a slot 24 and through these slots studs 25 carried by the fuel chamber extend and by means of nuts 26 threaded on the outer ends of said studs and cooperating with the slotted arms the chambers are 75 secured or maintained in proper relation.

In practice the inlet nipple 16 is coupled 80 or connected to the supply of fuel and the mixing chamber and fuel chamber are adjusted to proper position or relation with respect to each other by manipulating the nuts 26 and sliding the chambers longitudinally with respect to each other and then securing them in proper position by tightening these nuts 26. When this adjustment has 85 90 95 100 105

been effected and the supply of fuel is turned on it fills the annular fuel space 15 and from this fuel space it is projected through the discharge orifices 20 into the mixing chamber. The fuel in the mixing chamber may either be entirely surrounded by inner and outer layers or stratas of air or it may simply be surrounded by an outer strata of air, this variation being effected by opening or 10 closing respectively the damper 18. In this manner the burner may be adapted to the various conditions and exigencies which have to be met and will in all events produce a uniform, complete and efficient mixture from 15 which the maximum degree of heat will be evolved.

We claim:—

1. In a burner of the character described, an enclosed annular fuel chamber comprising inner and outer spaced circular walls and lateral walls or faces integral with said circular walls and defining an annular fuel space, one of said lateral walls being provided with a series of discharge orifices, said 20 inner circular wall defining an axial air inlet, a swinging damper for said air inlet, an open ended shell defining a mixing chamber, the fuel chamber being arranged adjacent one of the open ends of said shell and the 25 open end of said mixing chamber adjacent said fuel chamber being of circular form whereby said fuel chamber and said mixing chamber define an annular air inlet, and means for maintaining said fuel chamber and said mixing chamber in proper relation including arms fixed to one of said chambers and having elongated slots therein, studs fixed to the other of said chambers projecting through said slots and nuts threaded on 30 said studs and cooperating with said arms.
2. In a burner of the character described, an enclosed annular fuel chamber comprising inner and outer spaced circular walls and lateral walls or faces integral with said circular walls and defining an annular fuel space, one of said lateral walls being provided with a series of discharge orifices, an open ended shell defining a mixing chamber, the fuel chamber being arranged adjacent one of the open ends of said shell and the 35 open end of said mixing chamber adjacent said fuel chamber being of circular form whereby said fuel chamber and said mixing chamber define an annular air inlet, and means for maintaining said fuel chamber and said mixing chamber in proper relation including arms fixed to one of said chambers and having elongated slots therein, studs fixed to the other of said chambers projecting through said slots and nuts threaded on 40 said studs and cooperating with said arms. 45
3. In a burner of the character described, an enclosed annular fuel chamber having a circular series of discharge orifices in one of its lateral faces, an open-ended shell defining a mixing chamber, said annular fuel chamber being arranged adjacent one of the open ends of said shell to define therewith an annular air inlet and means for maintaining said fuel chamber and said mixing chamber in proper relation, including arms fixed to one of said chambers and having elongated slots therein and studs and nuts cooperating with said slotted arms. 50 55 60 65 70
